CLAIM

The ornamental design for a store facade, as shown and described.

DESCRIPTION

FIG. 1 is a front elevational view of a retail store facade showing my new design therefor;

FIG. 2 is a top plan view thereof;

FIG. 3 is a right side elevational view of the design of FIG. 1; and,

FIG. 4 is a left side elevational view of the design of FIG. 1.

The broken lines are for illustrative purposes only and form no part of the claimed design.
